UNITED STATES PATENT OFFICE.

JOHN P. ODGERS, OF PHILADELPHIA, PENNSYLVANIA, ASSIGNOR TO THE
A. M. COLLINS MANUFACTURING COMPANY, OF SAME PLACE.

DESIGN FOR A CARD-MOUNT.

SPECIFICATION forming part of Design No. 32,568, dated April 24, 1900.

Application filed December 23, 1899. Serial No. 741,477. Term of patent 7 years.

To all whom it may concern:

Be it known that I, JOHN P. ODGERS, a citizen of the United States, and a resident of Philadelphia, Pennsylvania, have invented or produced a new and original Design for a Photographic-Card Mount, of which the following is a specification.

My design is fully shown in the accompanying drawings, in which—

10 Figure 1 represents a face view of a card-mount illustrating the design, and Fig. 2 is a transverse section of the same on the line xx .

15 The design comprises a border 1, surrounding the panel for the reception of the picture, this border being composed of relief-bands 2, composed of successive scrolls and successive segments of scrolls, the latter characterizing the outer bands of the series. At the inner edge of the border is a rib 3.

20 The design for the ornamentation of a card-

mount, as herein described, may be applied to card-mounts with borders of different contours, the essential feature of the design consisting of a card-mount having ornamentation composed of the border made up of bands ²⁵ in relief each composed of a succession of scrolls.

I claim—

The design for a card-mount having the ornamentation substantially as herein described and as shown in the accompanying drawings. ³⁰

In testimony whereof I have signed my name to this specification in the presence of two subscribing witnesses.

JOHN P. ODGERS.
